UNITED STATES PATENT OFFICE.

MAHLON O. KASSON, OF CHICAGO, ILLINOIS.

INTERNAL-COMBUSTION MOTOR.

1,152,024.

Specification of Letters Patent. Patented Aug. 31, 1915.

Application filed November 29, 1912. Serial No. 734,137.

To all whom it may concern:

Be it known that I, MAHLON O. KASSON, citizen of the United States, residing at Chicago, in the county of Cook and State of Illinois, have invented certain new and useful Improvements in Internal-Combustion Motors; and I do hereby declare the following to be a full, clear, and exact description of the invention, such as will enable others skilled in the art to which it appertains to make and use the same.

This invention has for its object to provide an internal combustion rotary motor, and consists in the features of construction and combinations of parts hereinafter fully described and particularly claimed.

In the accompanying drawings illustrating the invention: Figure —1— is an end elevation of a motor embodying the invention. Fig. —2— is a central vertical longitudinal section of the same on the line 2—2 of Fig. —1—. Fig. —3— is a detail vertical transverse section of the same on the line 3—3 of Fig. —2—. Figs. —4— and —5— are respectively diagrammatic views illustrating different electric circuits and the means and manner of opening and closing the same whereby the explosion of gases in the cylinders is effected.

Many attempts have been made to produce an efficient rotary motor of the internal combustion type but, so far as I am informed, these have proved to be commercially impractical for the reason that the charges of combustible fluid to be exploded to provide the motive force were not compressed to a sufficient extent prior to ignition to yield the degree of expansive efficiency upon which motor efficiency is dependent. Such motors have, so far as I am informed, been designed to ignite the charge while disposed between the relatively movable parts to be actuated by expansion thereof, and, because of the lack of compression above referred to, and also to other difficulties presented by this class of motors, the increase in pressure due to expansion by ignition has been too small to yield commercial efficiency.

My invention is intended to overcome this difficulty by utilizing the gases after their ignition and exhaust from one or more com-

bustion chambers to develop power, *i. e.* propulsive mechanical movement. In other words, I propose to employ the products of combustion under pressure in a manner similar to that in which steam under pressure is utilized. The problem presented appears to be most easily solved in the rotary type of motor, the most successful example of which is seen in the turbine. I have, therefore, illustrated the invention as embodied in this type of motor or engine but the principle or law of nature upon which it is based may be capable of application to other forms or types of motors.

The embodiment of the invention illustrated comprises two main parts, *viz*: that part which generates and directs the motive force, and that part upon which it is directed and by means of which it is transformed into propulsive mechanical motion. The latter is best exemplified by the turbine which is diagrammatically illustrated and may be variously constructed to best utilize the motive force by persons skilled in turbine engineering. Means must be provided for utilizing a part of the motive force for actuating its generator. In that part of the motor which generates the motive force I utilize centrifugal force in maintaining the combustible charge under compression at the time of ignition and for discharging the products of combustion under pressure into the turbine end of the motor. Hence, a part of the power generated must be absorbed by the generating medium for the performance of its function as in all of the approved types of internal combustion motors.

The general object of the invention will be readily understood from the foregoing. This may be more specifically stated as follows:

One object of my invention is to provide a rotary motor of the internal combustion type in which the gases to be exploded are compressed prior to ignition whereby an explosive force of considerable magnitude is obtained.

A further object of the invention is to provide means whereby the discharge of each ignited charge from an explosive or combustion chamber into the means adapted to be actuated thereby is followed by a discharge

of cool compressed air into such means for the purpose of cooling and also actuating the same.

Another object of the invention is to provide means whereby the relative rotation of parts of the means actuated by the discharge of burnt gases provides a force which is utilized for maintaining a relatively constant pressure on the products of combustion during discharge thereof for actuating the said means.

Other objects of the invention will appear from the following description.

The motor as illustrated comprises the shaft 1 suitably journaled in bearings 2 and 3 disposed in standards 4 of any suitable construction and which carries a plurality of disks 5 equipped with annular flanges 6 from which blades 7 angularly disposed relatively to the axis of the shaft 1 project radially and which are connected together at their outer ends by means of a rim 7^a concentric with the flanges 6. The said disks 5 and the parts carried thereby alternate with similar disks 8 and blades 9, the latter angularly disposed relatively to the axis of the shaft 1 in a direction opposite to the planes of the blades 7 whereby zig zag passages are provided between contiguous alternate pairs of said blades 7 and 9. The said blades 9 are integral at their outer ends with the casing rings 10. Each of the latter is provided with an annular recess 11 contiguous to one end thereof in which a rim 7^a of the blades 35 or vanes of a disk 5 is rotatable. All of the casing rings 10 are also provided with outwardly extending annular flanges 12 which are adapted to be bolted or otherwise secured together to couple all of said rings 10 into a housing or casing. The latter is provided with an end wall 13 having an exhaust chamber 14 which connects with the exhaust port 15 for gases. Said casing is similarly provided with an end wall 16 which carries the combustion cylinders 17 and a rotary compressor casing 25, which will be hereinafter more particularly described.

The details of construction of the members 5 and 8 respectively, and the relative angular disposition of their blades 6 and 9 does not constitute, in the specific form herein shown, a part of the invention as said parts may be changed and varied in accordance with turbine engineering practice for the attainment of the best results without departing from the invention. The accompanying drawings are to be considered as showing merely diagrammatically a structure suitable for my purposes without particular regard to specific details of construction.

Disposed upon the end wall 13 of the turbine casing is a bevel gear 18 and carried rigid with the shaft 1 is a similar bevel gear 19, the face of which is opposed to the gear 18. Bevel pinions 20 carried by shafts 21

suitably journaled in bearings carried by one of the standards 4 mesh with both said gears 18 and 19 and cause the casing of the turbine to rotate in a direction opposite to the direction of rotation of the shaft 1 and parts carried thereby, and in the instance illustrated, at the same speed. The relative speeds of rotation may be varied at will without departing from the invention. The said shaft 1 is hollow contiguous to its other end and is connected at said end with a suitable supply of carbureted air, such for example as the carburetor 22 shown diagrammatically in Fig. —2—. Said shaft is provided with ports 23 through which the carbureted air or other combustible mixture is admitted to the central chamber 24 of the compressor 25. The latter, as herein shown, is of the rotary type, this being deemed a suitable type for use in this connection, though any other type may be substituted without departing from the invention.

The compressor herein shown comprises a cylindrical casing 26 and an inner concentric casing member 27, the latter being disposed to rotate with the shaft 1 and the former to rotate with the end wall 16 of the casing. Disposed between said members 26 and 27 and rigid with the end wall 16 of the turbine casing is a cylindrical member 28. The said member 28 is disposed eccentrically relatively to the members 26 and 27 and is provided with a port 29 establishing communication between the respective chambers on either side thereof; said port 29 being located at the point in the member 28 which is disposed radially nearest to the axis of the shaft 1.

The member 27 is provided with a plurality of ports 30 each controlled by spring-actuated check valve 31 and through which the explosive gaseous mixture is adapted to pass from the inner chamber 24 of the compressor to the chamber 32 between the members 27 and 28. The member 27 carries a plurality of blades or piston members 33 which, as herein diagrammatically shown, are each pivotally connected with said member 27 and at their outer ends are adapted to contact with the inner wall of the member 28, said blades being of a width equal to the width of the chamber 32 and constructed similarly to similar or equivalent piston members of rotary compressors to provide substantially fluid-tight joints between the several edges thereof and the parts with which they contact. The said blades 33 are normally held in position so that their outer edges contact with the inner wall of the member 28 by means of springs 34 which supplement the centrifugal force which, during rotation of the member 27, would cause said blades to remain normally in the positions shown in Fig. —3—. Each of said blades 33 is pivotally

secured in a suitable manner to the member 27 between two contiguous ports 30 in the latter, thus dividing the chamber 32 into four parts, each of which is equipped with 5 a check valve controlled inlet port 30 and each of which exhausts through the port 29 into the chamber 35 between the member 28 and the member 26. Obviously, during the relative rotation of the members 27 and 10 28 the gases contained in the several chambers between contiguous blades 33 will be compressed and will attain the greatest degree of compression at the time that each blade approaches the exhaust port 29 15 through which the compressed gases are then exhausted. The illustration of the compressor is purely diagrammatic and exemplary.

The several cylinders 17 are also rigidly 20 mounted on the said end wall 16 of the turbine casing. Each of the same is provided with a main chamber 36 and an auxiliary chamber 37 of smaller diameter. The upper end portion of the chamber 36 of the cylinder 25 communicates by means of a pipe 38 connecting with a passage 39 in the cylinder head and through a port 40 controlled by the check valve 41 with the chamber 35 from which it receives a supply of combustible 30 gas under pressure. In each of said cylinders there is provided a reciprocating piston 42 of the trunk type which is provided with an extension portion 43 of smaller diameter fitting and reciprocally movable in 35 the portion 37 of said cylinder, said piston being hollow for reasons which will hereinafter appear. Each of said pistons 42 is adapted to be normally held at the outer limit of its movement by centrifugal force 40 imparted thereto by the rotation of the turbine casing and is adapted to be moved toward the inner limit of its movement against the action of said centrifugal force by the action of the compressed gases entering the 45 same through said port 40. The degree of compression of the gases to be exploded in the several cylinders 17 will depend primarily upon the pressure in the chamber 35 and upon the weight of each of said pistons 42, its distance from the axis of rotation, and the speed of rotation. The pressure in said chamber 35 must be sufficient primarily to overcome the springs controlling the valves 41 and the centrifugal force 55 maintaining the pistons at the outer limits of their movement.

The pistons of the cylinders are free to rotate within the latter and, therefore, in order to provide means for electrically 60 igniting the charge as the latter is introduced in each cylinder the port 40 is disposed to one side of the center of the cylinder head and a sparking device or spark plug is introduced into the center of said head. This consists of a plug of fiber or

other nonconductive material which is equipped with two spring terminals 43, each of which is connected with one pole of a battery or other source of current as shown in the drawings and hereinafter described. The said terminals 44 are disposed in a central recess in the cylinder head below the plug 43. The piston is provided in its upper end centrally with a recess in which a pin 45 of metal is received, the latter having a tapered upper end portion which as said piston approaches the outer limit of its movement passes between the terminals 44 and thereby closes the electric circuit between the same. As the explosive charge under pressure forces the piston inwardly the said pin 45 will be withdrawn from engagement with said terminals 44 thus breaking the circuit and causing a spark to jump at this point thereby igniting the charge and exploding it. The increase in pressure due to the explosion of the charge will immediately close the check valve 41 and force the piston toward the lower limit of its movement. Said piston when at or near the outer limit of its movement covers the exhaust port 46 through which the exploded charge is projected into the turbine portion of the motor. This port is relatively small so that the pressure in the upper portion of the cylinder 17 cannot instantly fall to zero but will exceed for a time at least, the pressure due to the centrifugal force exerted upon the piston to force the latter farther toward the lower limit of its movement.

The lower end portion 37 of the cylinder is provided contiguous to its outer end with a plurality of ports 47 through which air may enter said cylinder. These ports are 105 adapted to be closed as the piston is forced downwardly by admission of the charge under pressure and its explosion thereby trapping the air contained in said portion 37. The lower end of the piston is equipped 110 with a head provided with a passage 48 which is controlled by the check valve 49 and through which and the passage 50 the air compressed in the portion 37 of the cylinder enters the inner chamber 51 of said piston. The air under pressure thus contained in said piston 51 is adapted to escape through a plurality of ports 52 in the upper end portion of said piston which communicate with an annular passage or groove 53 in 115 said piston which, however, is maintained sealed until said piston again moves toward the outer limit of its movement and said groove 53 communicates with the exhaust port 46 whereupon said air under pressure 120 thus trapped within the piston is exhausted into the turbine end of the motor where it not only exerts its force toward propulsion but by reason of its being cool serves to reduce the temperature within the said turbine. 125

The portion 54 of the cylinder disposed between the wall 55 at the lower end of the portion 36 and the upper end of the portion 37 is provided with an inlet and exhaust port 56 through which air is exhausted and received as said piston reciprocates. The lower end portion 37 of said piston is also provided with a check valve control inlet port 57 through which air may enter as said piston moves toward the outer limit of its movement after receiving a charge of compressed air from said portion 37 of said cylinder.

The motor may be operated in two different ways so far as the explosion of charges in the various cylinders is concerned as will be readily understood when it is considered that there is no valve mechanism controlled by the piston movements and in turn controlling the admission and exhaust of charges. The charge is always seeking to enter the cylinder and will do so as soon as the pressure on the inner face of the check valve 41 recedes to a point below that which the charge pressure can overcome. This would obviously follow each discharge from the cylinder so that the frequency of explosions alone controls the admission of fresh charges. Obviously this may take place a few or a great number of times per revolution in each cylinder depending entirely upon the system of ignition used. The ignition may be accomplished in a number of different ways. The preferable way is to provide a separate source of current for each cylinder so that the charges may be received and ignited therein just as frequently as this can be accomplished. All other systems of ignition must probably be of such a nature as to time the explosions so that each charge is exploded in each cylinder as the latter passes one or more points in its rotation about the turbine axis.

I have diagrammatically illustrated two systems of ignition adapted to the purpose which I will now proceed to describe.

In Fig. —4— I have diagrammatically illustrated a system of ignition which is untimed. This comprises a pair of terminals 44 in each cylinder each connected with one end of the secondary winding of an induction coil 58 mounted to rotate with the cylinders 7. A pin 45 (shown in Fig. —3—) mounted in the center of the piston contacts with both terminals and maintains the secondary circuit normally closed. As the piston is forced inwardly by an entering charge, the pin 45 is withdrawn and opens the circuit whereupon sparks will jump between said terminals 44 and ignite such charge. The primary winding of the coil 58 (equipped with the usual make and break armature) is grounded at one end 59 and the other end connects with brush 60 rotat-

ing with cylinders and having contact with 65 a ring 61 on a disk 62 rigid with the bearing 3, said ring being connected with one pole of a source of current 63, the other pole of the latter being grounded.

In Fig. —5— I have illustrated a timed 70 ignition in which the pin 45 is omitted, an ordinary jump-spark plug being used. The terminals of this plug connect with the respective ends of the secondary winding of the induction coil 69 rotating with the cylinder. The primary winding of the latter is connected through the make and break with a brush 65 contacting with a ring 66 of non-conductive material having metallic contact pieces 67 interposed therein at intervals all 80 of which are electrically connected with each other and with one pole of a source of current 68, the other pole of which is grounded as is also the other end of the primary winding of the induction coil 69. 85 Each time that the brush 65 passes over a contact piece 67 the primary coil circuit will be closed through the make and break thereby energizing the secondary coil and producing a jump spark to ignite the charge in 90 the cylinder. One ring 66 and coil 69 is provided for each cylinder, the number of explosions and time of the latter in the cylinders being determined by the number and relative location of the contact pieces 67 in 95 the several rings. The timed ignition is not deemed to be quite as advantageous as the untimed for the reason that the cylinders may receive too small a charge between intervals of ignition, or on the other hand, 100 they may receive too great a charge, that is to say, the pistons may, between intervals of ignition, be forced back by the incoming charge so as to uncover the exhaust ports and thus permit a part of the charges to 105 pass into the turbine without being ignited. This should obviously be avoided, and is, of course, possible to avoid by introducing the charge at a uniform pressure at all times and having such charge resisted not only by 110 the centrifugal force exerted on the pistons but also by a resisting pressure produced in the lower end portions of the cylinders by compressing the air contained therein during the inward stroke of the piston. In 115 this way an equalization of pressures within the cylinder and in the feed for the cylinder may be provided at a point in the stroke of the piston outwardly of the exhaust port. With such an arrangement the timed ignition may present advantages over the untimed but any suitable mode of ignition may be used without departing from the invention.

It will be apparent that the energy generated by ignition of the gases is most efficiently directed into actuating relation to the relatively rotating parts of the motor

by introducing the products of combustion under pressure into the same. This, however, heats the respective parts so that in some instances it might be advisable to direct this energy so that it will be indirectly exerted upon said relatively movable parts. This is partly exemplified in the drawings by using a part of said energy to compress air which is then introduced into actuating relation to said parts. While, as shown, the compressed air charges absorb only a part of the thermal energy the structure might be further modified to utilize a larger part or substantially all of the energy in this way. The mode of utilization of the power generated, that is, by directly exhausting the products of combustion under pressure into the turbine end of the motor is believed to be the most economical and preferable and subject to modifications indicated, is the only mode of utilization contemplated.

The operation of the motor or particularly the pistons in the cylinders is as follows: The centrifugal force exerted on the pistons will, of course, vary as the speed of rotation of the cylinders varies. Hence, the pressure of the gas delivered by the pump must be sufficient at all times to overcome that force. Thus a charge will enter a cylinder and force the piston inwardly and in so doing the pin 43 will be withdrawn from engagement between the terminals 44 thereby causing an ignition spark to pass between said terminals as previously described. The charge is now ignited and in expanding forces the piston farther inwardly so that it will uncover the exhaust port 46 whereupon the charge will pass into the turbine chamber into which it will be delivered under the constant pressure of the centrifugal force exerted by the piston, the inward motion of which will be arrested by the decrease in pressure due to the opening of the exhaust. The inlet port 40 is so proportioned to the cylinder as to feed rather slowly into the same while the exhaust port is relatively large so that the exhaust takes place very rapidly and permits a drop in pressure to a very low point the moment the piston uncovers said port. Accordingly a fresh incoming charge could not provide sufficient resistance in time to prevent the return of the piston to its normal position.

I claim as my invention:

1. In an internal combustion motor, a cylinder rotatable about an axis, the axis of said cylinder radially disposed relatively to said axis about which it rotates, a piston reciprocably movable in said cylinder and adapted to be maintained normally at the outer limit of its movement by centrifugal force, a source of combustible gas under pressure sufficient to overcome the centrifugal force exerted on said piston con-

nected with the outer end of said cylinder, means for igniting a charge of gas within the cylinder as said piston is forced thereby toward the inner limit of its movement, a lateral exhaust port for said cylinder between the limits of movement of said piston, and means disposed in the path of the exhausted charge and adapted to be acted upon thereby for transforming the force thereof into rotary motion whereby the cylinder is maintained in motion.

2. In an internal combustion engine, a cylinder rotatable about an axis, a piston reciprocably movable in said cylinder in a direction radial of said axis and adapted to be maintained by centrifugal force at the outer limit of its movement, a source of combustible fluid under pressure communicating with the outer end of said cylinder and adapted to force said piston inwardly against the action of centrifugal force, means for igniting the charge of combustible fluid in said cylinder as said piston reaches a predetermined point in its stroke, an exhaust port normally maintained closed by said piston and through which the ignited charge is exhausted under pressure as said piston is forced inwardly by the expansion thereof, and means disposed in the path of said exhausted charge and actuated thereby to transform its force into rotary motion, a part of said force exerted to maintain said cylinder in rotation about said axis.

3. An internal combustion motor comprising two relatively rotatable parts adapted to be actuated by the products of combustion under pressure, a cylinder carried by one of said parts and exhausting the products of combustion to impinge upon the other part, a piston reciprocably movable in said cylinder and maintained by centrifugal force at the outer limit of its movement within said cylinder, a source of combustible fluid having check-valve-controlled connection with the outer end of said cylinder and supplying said fluid to said cylinder at a pressure sufficient to overcome the centrifugal force actuating said piston, means for igniting the fluid in said cylinder as said piston is moved inwardly thereby, said piston adapted to be forced farther inwardly as the same is exploded, an exhaust port from said cylinder normally maintained closed by said piston and adapted to be uncovered as the latter is forced inwardly by explosion of fluid.

4. In an internal combustion engine, a member rotatable about an axis and carrying a plurality of radially disposed cylinders, a piston for each cylinder maintained normally at the outer limit of its movement by centrifugal force, a source of supply of combustible fluid under pressure having check-valve controlled connection with the

- outer end of said cylinder, said fluid maintained under pressure sufficient to overcome the centrifugal force acting on said pistons and adapted to force the latter inwardly, 5 means for igniting the fluid within the outer end portion of each cylinder as said piston is moved inwardly, an exhaust port for each cylinder normally maintained closed by its piston and adapted to be uncovered as said piston is moved inwardly by the explosion of the charge, the products of combustion being exhausted under pressure exerted thereon by the piston, and 10 means communicating with said exhaust port for converting the pressure of said exhaust gases into mechanical movement, whereby said cylinder-carrying member is maintained in rotation.
5. In an internal combustion engine, a 20 member rotatable about an axis and carrying a plurality of radially disposed cylinders, a piston for each cylinder maintained normally at the outer limit of its movement by centrifugal force, a source of supply of combustible fluid under pressure having check-valve controlled connection with the outer end of said cylinder, said fluid maintained under pressure sufficient to overcome the centrifugal force acting on said pistons 25 and adapted to force the latter inwardly, means for igniting the fluid within the outer end portion of each cylinder as said piston is moved inwardly, an exhaust port for each cylinder normally maintained closed by its piston and adapted to be uncovered as said piston is moved inwardly by the explosion of the charge, the products of combustion being exhausted under 30 pressure exerted thereon by the piston, means communicating with said exhaust port for converting the pressure of said exhaust gases into mechanical movement, whereby said cylinder-carrying member is maintained in rotation, and a compressor 35 for the combustible fluid actuated by relative movement of said cylinder-carrying part and said last-named means.
6. In an internal combustion engine, the 40 combination with two members adapted to be actuated to rotate relatively to each other by gas under pressure, of a plurality of cylinders carried by one of said members, a piston for each cylinder reciprocable in the direction of a radius of the axis of rotation 45 of said member and adapted to be maintained at the outer limit of its movement by centrifugal force as said member rotates, a source of combustible fluid under pressure having valve-controlled connection with the outer end of each cylinder and adapted to supply said cylinder against the action of said centrifugal force, means for igniting the fluid in each cylinder as the piston is moved inwardly thereby, and an exhaust port from each cylinder arranged to be un-

covered by the piston as the latter is forced inwardly by explosion of the fluid and adapted to discharge said fluid into actuating relation to said respective members.

7. In an internal combustion engine, the 70 combination with two members adapted to be actuated to rotate relatively to each other by gas under pressure, of a plurality of cylinders carried by one of said members, a piston for each cylinder reciprocable in the 75 direction of a radius of the axis of rotation of said member and adapted to be maintained at the outer limit of its movement by centrifugal force as said member rotates, a compressor for combustible fluid operatively connected with and actuated by said cylinder-carrying member, and communicating with the outer ends of said cylinders to supply the same against the action of said centrifugal force, means for igniting the fluid 80 in each cylinder as the piston is moved inwardly thereby, and an exhaust port from each cylinder arranged to be uncovered by the piston as the latter is forced inwardly by explosion of the fluid and adapted to discharge said fluid into actuating relation to 85 said respective members.

8. An internal combustion motor comprising two parts geared to rotate in opposite directions about a common axis, and adapted to be actuated by a fluid under pressure, at least one combustion chamber carried by one of said parts for supplying fluid under pressure, a centrifugally actuated piston in said chamber, means for supplying combustible fluid under pressure to said combustion chamber, and means for igniting the same therein for actuating said piston against centrifugal forces and discharging the ignited fluid into actuating relation to 95 said parts.

9. An internal combustion motor comprising two parts geared to rotate in opposite directions about a common axis, and adapted to be actuated by a fluid under pressure, at least one combustion chamber carried by one of said parts for supplying the fluid under pressure, a centrifugally actuated piston in said chamber, means for supplying combustible fluid under pressure to said combustion chamber, means for igniting the same therein for actuating said piston against centrifugal forces and discharging the ignited fluid into actuating relation to 100 said parts, and means for maintaining the 110 ignited charge under pressure during exhaust thereof from said combustion chamber.

10. An internal combustion motor comprising two parts geared to rotate in opposite directions about a common axis, and adapted to be actuated by a fluid under pressure, at least one combustion chamber carried by one of said parts for supplying the fluid under pressure, a piston in said 125 130

combustion chamber normally maintained at one limit of its movement, means for supplying combustible fluid under pressure to said combustion chamber against the action of said piston, means for igniting the fluid within said chamber, an exhaust port from said chamber disposed to discharge the products of combustion into actuating relation to said relatively rotating parts and adapted to be opened by movement of the piston induced by the combustion of said fluid.

11. An internal combustion motor comprising two parts geared to rotate in opposite directions about a common axis, and adapted to be actuated by a fluid under pressure, at least one combustion chamber carried by one of said parts for supplying the fluid under pressure, a piston in said combustion chamber normally maintained by centrifugal force at the outer limit of its movement, means for supplying combustible fluid under pressure to said combustion chamber against the centrifugal actuation of said piston, means for igniting the fluid within said chamber, an exhaust port from said chamber disposed to discharge the products of combustion into actuating relation to said relatively rotating parts and adapted to be opened by movement of the piston induced by the combustion of said fluid.

12. An internal combustion motor comprising two parts geared to rotate in opposite directions about a common axis, and adapted to be actuated by a fluid under pressure, at least one combustion chamber carried by one of said parts for supplying the fluid under pressure, a piston in said combustion chamber maintained normally at one limit of its movement and adapted to be forced to the other limit of its movement by the explosion of a combustible charge in said chamber, an air chamber at the other end of said piston adapted to supply a charge of compressed air at each movement of said piston into said chamber, means for introducing said compressed air into actuating relation to said relatively rotatable parts, means for supplying combustible fluid to said combustion chamber, and means for igniting and discharging the same.

13. An internal combustion motor comprising two parts geared to rotate in opposite directions about a common axis, and adapted to be actuated by a fluid under pressure, at least one combustion chamber carried by one of said parts for supplying the fluid under pressure, a piston in said combustion chamber maintained normally at one limit of its movement and adapted to be forced to the other limit of its movement by the explosion of a combustible charge in said chamber, an air chamber at the other end of said piston adapted to supply a charge of compressed air at each movement

of said piston into said chamber, means for introducing said compressed air into actuating relation to said relatively rotatable parts, means for supplying combustible fluid to said combustion chamber, means for igniting the same, and means for discharging the ignited charge into actuating relation to said relatively rotatable parts.

14. An internal combustion engine comprising two parts, one of which is adapted to rotate relatively to the other, at least one combustion chamber carried by said rotatable part, means for supplying the latter with combustible fluid under pressure, means for igniting said fluid, an air compressor, means adapted to be actuated by the expansion of said ignited charge in said combustion chamber, and means for delivering the compressed air into actuating relation to said first-named motor parts.

15. An internal combustion motor comprising two parts, one of which is adapted to rotate relatively to the other, at least one combustion chamber carried by said rotatable part, means for supplying said chamber with combustible fluid, means for igniting the fluid contained within said chamber, an air compressor, means adapted to be actuated by expansion of said ignited charge in said combustion chamber, and means for delivering the compressed air into actuating relation to said first-named motor parts.

16. An internal combustion motor comprising two parts, one of which is adapted to rotate relatively to the other, at least one combustion cylinder carried by said rotatable part, a piston for said cylinder normally maintained at one limit of its movement within said cylinder, means for introducing combustible fluid under pressure into said cylinder, means for igniting the same for forcing the piston toward the other limit of its movement, an air compressor cylinder, a piston for the same connected with the first-named piston and actuated thereby to compress air as said first-named piston is moved by said ignited charge, means for directing the products of combustion under pressure into actuating relation to said motor parts, and means for directing the compressed air into such actuating relation to said parts.

17. An internal combustion motor comprising two parts, one of which is adapted to rotate relatively to the other, at least one combustion cylinder carried by said rotatable part, a piston for said cylinder normally maintained at one limit of its movement within said cylinder, means for introducing combustible fluid under pressure into said cylinder, means for igniting the same for forcing the piston toward the other limit of its movement, an air compressor cylinder, a piston for the same connected with the first-named piston and actuated thereby to

compress air as said first-named piston is moved by said ignited charge, means for directing the products of combustion under pressure into actuating relation to said motor parts, and means for directing the compressed air into such actuating relation to said parts subsequent to the direction of said products of combustion into the same.

18. An internal combustion motor comprising two parts, one of which is adapted to rotate relatively to the other, at least one combustion cylinder carried by said rotatable part, a piston for said cylinder normally maintained at one limit of its movement within said cylinder, by centrifugal force, means for introducing successive charges of combustible gas into said cylinder against the centrifugal force actuating said piston, means for igniting the same for forcing the piston toward the other limit of its movement, an air compressor cylinder, a piston for the same connected with the first-named piston and actuated thereby to compress air as said first-named piston is moved by said ignited charge, means for directing the products of combustion under pressure exerted by return movement of said piston into actuating relation to said motor parts, and means for directing the compressed air into such actuating relation to the said parts.

19. An internal combustion motor comprising two parts, one of which is adapted to rotate relatively to the other, at least one combustion chamber, a combustion cylinder and an air compressor cylinder carried by said rotatable part, a single piston common to both said cylinders and maintained by centrifugal force normally at one limit of its movement, means for introducing successive explosive charges into said combustion chamber against the action of the centrifugal force actuating said piston and igniting said charges to force said piston toward the other limit of its movement at successive intervals, whereby compression of air is effected, means for directing the products of combustion under the pressure of the return movement of said piston into actuating relation to said motor parts, and means for directing the compressed air into such actuating relation to said parts.

20. An internal combustion motor comprising two parts, one of which is adapted to rotate relatively to the other, at least one combustion chamber, a combustion cylinder and an air compressor cylinder carried by said rotatable part, a single piston common to both said cylinders and maintained by centrifugal force normally at one limit of its movement, means for introducing successive explosive charges into said combustion chamber against the action of the centrifugal force actuating said piston, and igniting said charges to force said piston toward the other limit of its movement at successive

intervals, whereby compression of air is effected, means for directing the products of combustion under the pressure of the return movement of said piston into actuating relation to said motor parts, a storage chamber for compressed air, and means for directing the contents of said storage chamber into actuating relation to the motor parts between the intervals of direction of the products of combustion into the same.

21. An internal combustion motor comprising two parts, one of which is adapted to rotate relatively to the other, at least one combustion chamber, a combustion cylinder and an air compressor cylinder carried by said rotatable part, a single piston common to both said cylinders and maintained by centrifugal force normally at one limit of its movement, means for introducing successive explosive charges into said combustion chamber against the action of the centrifugal force actuating said piston and igniting said charges to force said piston toward the other limit of its movement at successive intervals, whereby compression of air is effected, a storage chamber for compressed air within said piston having check valve controlled communication with said air compressor cylinder and adapted to receive and trap the successive charges of compressed air, an exhaust port for products of combustion from said cylinder uncovered by said piston as the latter is actuated by explosion of a charge and through which said products of combustion are adapted to be directed into actuating relation to the motor parts, and an exhaust port in said piston adapted to communicate with the exhaust port from said cylinder as said piston returns to its normal position.

22. An internal combustion motor comprising two parts, one of which is adapted to rotate relatively to the other, at least one combustion chamber, a combustion cylinder and an air compressor cylinder carried by said rotatable part, a single piston common to both said cylinders and maintained by centrifugal force normally at one limit of its movement, means for introducing successive explosive charges into said combustion chamber against the action of the centrifugal force actuating said piston and igniting said charges to force said piston toward the other limit of its movement at successive intervals, whereby compression of air is effected, a storage chamber for compressed air within said piston having check valve controlled communication with said air compressor cylinder and adapted to receive and trap the successive charges of compressed air, an exhaust port for products of combustion from said cylinder uncovered by said piston as the latter is actuated by explosion of a charge and through which said products of combustion are adapted to be

directed into actuating relation to the motor parts, and an exhaust port in said piston communicating with an annular groove therein adapted to register with the exhaust port of said cylinder as said piston returns to its normal position.

In testimony whereof I have signed my

name in presence of two subscribing witnesses.

MAHLON O. KASSON.
